United States Patent

Des. 235,674
Patented July 1, 1975

235,674

HAND OPERATED CULTIVATOR

Don L. Calder, 936 W. 8th Ave., Mesa, Ariz. 85201

Filed Oct. 3, 1973, Ser. No. 403,217

Term of patent 14 years

Int. Cl. D15—03

U.S. Cl. D35—2 A

FIG. 1 is a perspective view from the front and left of a hand operated cultivator showing my new design.

FIG. 2 is a perspective view taken from the rear and below of a second embodiment of the design shown in FIG. 1.

FIG. 3 is an enlarged partial perspective view of the design shown in FIG. 1.

I claim:

The ornamental design for a hand operated cultivator, as shown and described.
